55,545.

Specification for Design. Patented June 29, 1920.

Application filed February 11, 1920. Serial No. 357,819. Term of patent 14 years.

To all whom it may concern:

Be it known that I, ARTHUR S. ALEXANDER, a citizen of the United States, residing in the city of New York, county and State of New York, have invented a new, original, and ornamental Design for a Mirroscope-Support, of which the following is a specification, reference being had to the accompanying drawing, forming a part hereof.

In the drawing,—

Figure 1 is a side view of my improved design;

Fig. 2 is a view from the rear; and
Fig. 3 is a view on the line 3—3 in the direction of the arrows.

I claim:—

The ornamental design for a microscope support, substantially as shown.

This specification signed this sixth day of February, 1920.

ARTHUR S. ALEXANDER.
